United States Patent Office

Des. 187,156
Patented Feb. 2, 1960

187,156

PLATE OR SIMILAR ARTICLE

Shigeru Masuda, Nagoya, Aichi, Japan, assignor to Noritake Co., Inc., New York, N.Y., a corporation of New York

Application August 24, 1959, Serial No. 57,291

Term of patent 7 years

(Cl. D44—15)

The figure is a plan view of a plate or similar article, showing my new design.

The plate is of a conventional configuration when viewed from the side and bottom thereof.

I claim:

The ornamental design for a plate or similar article, substantially as shown and described.
